UNITED STATES PATENT OFFICE.

CHARLES L. RAYFIELD, OF CHICAGO, ILLINOIS, ASSIGNOR TO BENEKE MANUFACTURING COMPANY, OF CHICAGO, ILLINOIS, A CORPORATION OF ILLINOIS.

CARBURETOR.

Application filed December 16, 1916. Serial No. 137,372.

To all whom it may concern:

Be it known that I, CHARLES L. RAYFIELD, a citizen of the United States, and a resident of the city of Chicago, in the county of Cook and State of Illinois, have invented certain new and useful Improvements in a Carburetor; and I do hereby declare that the following is a full, clear, and exact description of the same, reference being had to the accompanying drawings, and to the numerals of reference marked thereon, which form a part of this specification.

This invention relates to a side outlet carburetor for an engine wherein a plurality of fuel jets are utilized, one operated by an auxiliary air valve, and another of which is normally open and manually actuatable to further open the same as well as adjustable to change the range of manual actuation thereof. The invention further utilizes means communicating directly with the manifold of an engine to draw raw gasoline into the manifold through a by-pass around the throttle valve when the throttle valve is open or closed, to afford an easy means of starting the engine.

It is an object therefore of this invention to construct a carburetor embracing a plurality of air inlet passages and fuel supply nozzles with means for adjustment of valves governing the inlet of air through said passages as well as the inlet of fuel, and with means for introducing raw fuel into the manifold of the engine through the carburetor beyond the throttle valve mounted in the outlet thereof.

It is also an object of this invention to construct a carburetor provided with a plurality of air inlet valves and fuel supply nozzles with one fuel nozzle controlled by one of said air supply valves and with means for inducing a flow of fuel under pressure to one of said fuel supply nozzles by a sudden opening movement of the air supply valves, and further, with means for introducing raw fuel directly from the carburetor supply chamber into the manifold of the engine to which the carburetor is attached, around the throttle valve when said throttle valve is open or is closed.

It is also an object of this invention to construct a carburetor provided with an adjustable normally open fuel supply nozzle and an auxiliary fuel supply nozzle adapted

to be actuated by an automatic air valve which also operates means to force fuel under pressure to both of said nozzles, together with means for increasing the opening of one of said nozzles as well as establishing direct communication from the carburetor fuel supply to the manifold of the engine independent of the carburetor outlet passage controlled by the throttle valve.

It is furthermore an important object of this invention to construct a carburetor provided with manually actuatable means for opening a fuel nozzle beyond normal, as well as to open a by-pass connection between the source of fuel supply and a point beyond the throttle valve of the carburetor to enrich the mixture drawn from the carburetor, and, if desired, to draw raw gasoline directly into the manifold of the engine when the throttle valve is closed to facilitate starting the motor.

It is finally an object of this invention to construct a carburetor provided with an improved type of air inlet valve mechanism wherein an automatic air valve serves to actuate a sleeve valve as well as operate an auxiliary fuel supply nozzle, furthermore opening a butterfly valve to admit the fuel and air into a mixing chamber provided with a manually adjustable normally open fuel supply valve actuatable by means capable of establishing communication between the source of fuel supply and the manifold of the engine around the throttle valve.

The invention (in a preferred form) is illustrated in the drawings and hereinafter more fully described.

In the drawings:

Figure 1 is a slightly enlarged section on the line A—A of Figure 2 with parts in elevation.

Figure 2 is a top plan view of the carburetor with the parts shown in the adjustment illustrated in Fig. 1.

Figure 3 is a view similar to Figure 1 with parts shown in elevation.

Figure 4 is a detail sectional view taken on line 4—4 of Fig. 3, with parts omitted.

Figure 5 is a sectional detail taken on line 5—5 of Fig. 3.

Figure 6 is a fragmentary detail section with parts omitted and parts shown in plan, taken on line 6—6 of Fig. 1.

Figure 7 is a sectional detail view on line 7—7 of Fig. 2.

Figure 8 is a detail section taken on line 8—8 of Fig. 2.

5 Figure 9 is an enlarged top plan view of the dash pot piston.

Figure 10 is a detail section taken on line 10—10 of Fig. 9.

10 Figure 11 is a detail section taken on line 11—11 of Fig. 2.

Figure 12 is a section on line 12—12 of Figure 1, with parts omitted and parts shown in bottom plan.

15 Figure 13 is a detail end view of one of the needle valves for a fuel nozzle.

Figure 14 is a fragmentary section detail through one side of the carburetor.

As shown in the drawings:

20 The carburetor consists of an integral casing comprising a float chamber 1, an air inlet chamber 2, and a mixing or carbureting chamber 3, the outlet from which is controlled by a throttle valve 4, secured on a pivot shaft 5, extending vertically 25 through the carburetor casing and actuatable by a throttle lever 6. Formed beneath the inlet air chamber 2, and separated therefrom by a partition or floor 7, is a dash pot chamber 8, the lower end of which is closed 30 by a large closure plug 9, sealingly engaged therein.

35 As clearly shown in Figure 11, a passage 10, communicates through the upper end of the dash pot chamber 8, into the float chamber 1, to permit fuel to flow into the dash pot chamber. Threaded into the lower end of the float chamber 1, is a passaged plug 11, and threaded thereinto is another passaged plug 12, which serves to clamp an annular or ring member 13, sealingly on the lower end of the float chamber, and said annular member 13, is provided with an inlet pipe 14, to admit fuel into the float chamber. A screen 15, is disposed around

45 the lower end of said passaged plug member 11, through which the fuel is admitted from the annular member 13 for passage into the float chamber. A spun metal float 16, is provided within the float chamber, 50 serving to control the movement of an admission valve for fuel through said associated plug members 11 and 12, in a manner well known in the art, and therefore not shown nor described in detail. A view 55 aperture provided with a disk of glass 17, is provided in one wall of the float chamber to ascertain the level of fluid therein, and said float chamber is closed at its upper end by a cover 18.

60 Extending into the upper end of the air inlet chamber 2, is a ring valve seat member 19, and adjustable to move into closed relation therewith is an automatic air inlet valve 20, mounted on the upper end of a 65 stem 21, which is slidably mounted through

an apertured boss formed on the floor or partition wall 7, at the bottom of the inlet air chamber, and at its lower end said stem is provided with a piston 22, movable in the dash pot chamber 8. A compression spring 70 23, is coiled about said stem 21, bearing upwardly beneath the valve 20, to normally thrust the same upwardly into closed relation with the ring member 19, said spring bearing downwardly upon the boss formed 75 on said partition floor 7. Communicating into one side of the air inlet chamber 2, is an air inlet port into which is secured a cylindrical valve cage or spider 24, having slidably mounted therein a cylindrical sleeve 80 valve 25. Surrounding and enclosing the outer end of the valve cage 24, is an integral rounded shield or hood, 26, open at its lower end through which the air is allowed to enter for passage through the valve cage 85 in amounts dependent upon the adjustment of the sleeve valve 25. Said shield and valve cage member, is held rigidly in position by two screws 28, threaded through the shield member into the end of the carburetor casing. A stem 29, is secured axially within said valve cage 24, and as clearly shown in Figs. 1 and 3, said sleeve valve 25, is provided with an elongated hub 30, slidable upon said stem 29, and provided with a deflecting head 31, at its inner end adapted to disperse the entering air peripherally therearound as it enters the chamber 2.

Pivoted at the entrance end of the mixing chamber 3, to control the flow of fluid from the air inlet chamber 2, thereinto, is a butterfly valve 32, connected to the inner end of the member 30, by a pair of long links or levers 33, one disposed on each side of the valve stem 21. Rigidly secured upon the under side of the automatic valve 20, is a yoke-shaped bracket 34, the extending arms of which are connected by links 35, to said respective levers 33.

Threaded into the partition floor 7, in the bottom of the air inlet chamber 2, is a fuel nozzle 36, which extends upwardly between the respective pairs of connected links and levers 33 and 35, and, as shown in detail in Fig. 14, provided on its interior with tubular member 37, which is secured to the piston 22, over an aperture 38 therethrough communicating with that portion of the dash pot chamber 8, beneath said piston. Slidably mounted within the tubular nozzle 36, is a tapered metering pin 39, which extends through the aperture in the upper end of said nozzle member 36, to a point beneath the automatic air valve 20. When the valve 20, moves downwardly, the same 115 will serve to thrust said metering pin 39, downwardly, thereby opening an annular orifice around the metering pin for exit of fuel. Said metering pin 39, is normally held thrust upwardly by a coiled compres- 120 125 130

sion spring 40, disposed within said nozzle 36, and bearing at its lower end upon an interior shoulder formed in the member 37.

As clearly shown in Fig. 14, said metering pin 39, is provided with a passage 41, therethrough, the upper end of which, when the metering pin 39, is depressed, is brought below the normal level of fluid in the float chamber so as to permit a flow of fuel there-
10 through. Threaded through an aperture in the lower wall of the mixing chamber 3, is an upright fuel nozzle 42, and formed beneath said nozzle is a small fuel chamber 43, closed by a threaded plug 44, receiving
15 fuel through a passage 45, communicating therewith and with the dash pot chamber 8. A tubular needle valve 46, having fuel pas-
sages therethrough, is provided to regulate the area of opening of the aperture at the up-
20 per end of the nozzle 42, and said needle valve is provided with a notched filler plug 47, mounted in the upper end thereof. Said tubular needle valve is slidably mounted
25 through a sleeve element 48, secured on the carburetor casing. A spring 49, is coiled within the upper end of the sleeve element 48, and bears downwardly upon the filler plug 47, of the needle valve, to normally impel said needle valve toward closed relation with the
30 fuel nozzle 42. A shell or sleeve element 46^a, is secured around the lower end of the needle valve 46, extending slightly below the upper end of the nozzle 42, and at its upper end provided with apertures in register with the
35 outlet passages in the needle valve.

As shown in detail in Figure 7, a notch 50, is provided in the filler plug 47, and engaged therein is a tail lever or tooth 51, of a crank 52, pivoted on the upper end of said member 48. Said crank 52, is provided with a set screw 53, having a knurled head 54, for adjustment of the same, held in different adjusted positions by a spring detent 55, mounted in an extension of said crank.
45 Journalled upon the upper end of the mem-
ber 48, as clearly shown in Figure 1, is a lever 56, having a cam shaped or eccentric hub ring 57, as clearly shown in Figures 2 and 8, adapted when said lever 56, is rotated
50 on the sleeve 48, to contact the end of the set screw 53, thereby causing pivotal movement of the crank 52, outwardly therefrom to elevate the tooth 51, of the crank, and con-
sequently lift the needle valve 46. An at-
55 taching or binding post 58, is provided on the outer end of the lever 56, for attachment of a lever or wire thereto to actuate said lever.

Mechanism is provided for introducing raw gasoline from the carburetor into the
60 manifold of the engine at two different points beyond the throttle valve 4, when the throttle valve is closed, or even if the same is open if the suction draft is sufficient for the purpose, which is brought into operation
65 by movement of the lever 56, from normal

transverse position relative the mixing cham-
ber 3 to a substantially longitudinal relation therewith. For this purpose, a small pipe
59, leads downwardly within the float cham-
ber 1, as clearly shown in Figure 11, and up-
70 wardly therefrom to the upper end of the air inlet chamber 2, and there communicates with a passage 59^a cored within the casing wall of said air inlet chamber 2, as clearly shown in Figure 1, and communicates into a
75 tubular boss 60, formed on the top wall of the mixing chamber 3. Another passage 61, formed within the top wall of the mixing chamber 3, communicates into said tubular boss 60, at another point therein, and leads
80 forwardly and communicates through the top wall of the mixing chamber 3, at a point beyond the throttle valve 4, therein, as clearly shown in Figure 12. A spring impelled
85 piston 60^a, is mounted within said boss 60,
and is normally positioned to close the pas-
sages which communicate into said boss 60,
but projects outwardly through the end of
90 the boss so as to be capable of being thrust
inwardly, thereby establishing communica-
tion between said passages through said tubular boss. However, when an exceedingly rich mixture is desired, as, for instance, when
95 the motor is cold, the lever 56, is rotated
counter-clockwise referring to Fig. 2, so that
a tail extension 62, formed on said lever 56,
will serve to thrust said piston 60^a, inwardly
in said tubular boss 60, as clearly shown in
100 Figure 2, and as a consequence, the suction
draft from the engine will be transmitted
through the passage 61, to the pipe 59, com-
municating therewith through the tubular
boss 60, and raw gasoline will be drawn up-
105 wardly through said passages for introduc-
tion into the engine manifold from the float
chamber of the carburetor. The adjustment
of the lever 56, in the manner described will
also serve to elevate the needle valve 46, into
110 open position to admit a large quantity of
fuel through the nozzle 42.

Another passage 61^a, is cored within the top wall of the mixing chamber 3, leading outwardly through the inner wall surface of the casing at a point beyond the throttle
115 valve 4, as shown in Figure 12. The tubular
needle valve 46, is provided with a port 61^b
near its upper end adapted to register with
said passage 61^a, when the lever 56, is swung
rearwardly and said needle valve 46, elevated
120 to open position so that a flow of fuel may
take place around the throttle valve if the
same is closed.

As clearly shown in Figure 2, a stop mem-
ber 63, is secured upon the outer end of the
pivot shaft 5, for the throttle valve 4,
125 adapted to strike against any suitable pro-
jection on the casing to limit the opening and
closing movements of the throttle valve, there
being a set screw 64, secured in said stop
member, adjustable to limit the closure of
130

the throttle valve to the desired amount whereby the engine to which the carburetor is connected may be permitted to properly idle at low speed.

5 Referring back to the dash pot piston 22, as shown in Figures 9 and 10, the same is provided with apertures 65, therethrough, and an automatically operating disk check valve 66, is slidably mounted on the under 10 side of the piston 22, adapted to close said apertures during downward movement of the piston and to open the same during upward movement thereof.

The operation is as follows:

15 The control of the quantity of fuel mixture flowing from the carburetor to the engine, is effected entirely by adjustment of the throttle valve 4, but adjustment of said throttle valve has no effect directly upon the 20 adjustment of the fuel or air inlet means for the carburetor; these means operating automatically to form a proper fuel mixture for all conditions of operation of the engine. The draft induced through the carburetor 25 by the engine causes the air valve 20, to be drawn downwardly and movement of this valve is transmitted to the butterfly valve 32, through the short links 33, which depress the long levers 33, to swing said butterfly 30 valve 32, toward open position. As the draft through the carburetor increases, the automatic valve 20, is drawn still further downwardly, thus not only swinging the long levers 33, downwardly, to open the butterfly valve 32, but thrusting the same forwardly so as to draw the cylindrical sleeve 25, inwardly, to open the auxiliary air 35 port through the shield 26. In any event, downward movement of the air valve 20, serves to depress the metering pin 39, which 40 controls the fuel nozzle 42, to allow a flow of fuel through the end or annular orifice thereof. Fuel also flows through the passage 41, before the metering pin is depressed. The 45 fuel nozzle 42, mounted within the mixing chamber 3, is normally open a predetermined amount, so that for idling speed of the engine, sufficient fuel for the purpose will be drawn through the nozzle 42. The adjustment of the normal opening of the nozzle 42, is readily effected by turning the knurled head 54, of the set screw 53, mounted in the crank 52, which maintains the needle valve 46, elevated against the stress of its 55 spring 49.

If it is desired to increase the quantity of fuel admitted to the mixture in the carburetor, as, for instance when the motor is cold, the lever 56, may be swung rearwardly an amount desired to rotate the cam 57, thereof, which, by causing movement of the crank 52, will elevate the needle valve slightly more than the normal amount for which it is adjusted. Means are provided 60 for introducing raw gasoline directly into

the manifold of the engine from the carburetor, as, for instance, when it is desired to start the engine. For this purpose, the lever 56, referred to, is swung counter-clockwise, referring to Figure 2, into its extreme 70 position rearwardly so that the extension 62, thereof, thrusts the piston 60^a, inwardly into the tubular boss 60, in the carburetor casing, and preferably, the throttle valve 4, is closed, so that when the engine is 75 turned over, the draft from the manifold thereof will be exerted through the passage 61, communicating around the throttle valve 4, through the tubular boss 60, and through the pipe 59, leading directly into the float 80 chamber 1, as shown in Fig. 11. Of course, the throttle valve may be opened if desired, and a flow of fuel will still take place issuing from the pipe 59, and passage 61, so long as the extension 62, of the lever 56, is held 85 against the end of the piston 60^a, to hold the same retarded.

The piston 22, disposed in the dash pot chamber 81 is connected for operation by the air valve 20, serving to prevent fluttering 90 of said valve 20, and the associated valves 25 and 32, operated thereby, so that an even steady movement thereof takes place in accordance with the changes in draft induced 95 through the carburetor according to operating conditions of the engine.

The fuel nozzle 42, affords an efficient means for carburetion of air, owing to the fact that a certain quantity of air is drawn upwardly through the shell or sleeve 46^a, 100 past the annular fuel orifice of the nozzle 42, and upwardly with the fuel through the passages in the needle valve itself for emission through the side outlet ports therein at the middle portion thereof, as shown in 105 Figure 7. Furthermore, a flow of fuel mixture may take place from through the port in the upper end of the tubular needle valve 46, through the passage 61^a, around the throttle valve 4, and when said throttle valve 110 4, is closed and said lever 56, is swung into its rearward extreme position, a supply of raw fuel will be drawn upwardly through the open needle valve 46, and introduced 115 around the throttle valve through the passage 61^a.

I am aware that the details of construction may be varied through a wide range without departing from the principles of this invention, and I therefore do not pur- 120 pose limiting the patent granted otherwise than necessitated by the prior art.

I claim as my invention:

1. In a carburetor of the class described the combination with a float chamber, air 125 inlets and fuel inlet means, of a throttle valve controlling the flow of mixture from the carburetor, a lever controlling the adjustment of said fuel inlet means, and means adapted to be operated at the limit of move- 130

ment of said lever to establish suction communication between the fuel in the float chamber and a point beyond the throttle valve of the carburetor to introduce raw fuel therethrough.

5. 2. The combination with a carburetor its fuel valve and its mixture outlet controlling means, of passages adapted for communication with one another and one thereof communicating with the fuel supply of the carburetor and the other directed to supply raw fuel into the carburetor at a point beyond said mixture outlet means, means disposed normally to close communication between said passages, and mechanism controlling adjustment of said fuel valve adapted to open said means to establish suction effect between said passage for introduction of raw fuel at a point beyond the mixture outlet means and independent of the adjustment thereof.

10. 3. In a carburetor, a mixing chamber, a throttle valve controlling the exit of the mixture from said chamber, a fuel supply means in said mixing chamber, means for adjusting the outlet of said fuel supply means to regulate the fuel supplied thereby while the throttle valve is open, and means rendered operative by the movement of said 15 adjusting means to the limit in one direction and by the closing of the throttle valve to supply fuel beyond the throttle valve.

4. In a carburetor having a mixing chamber, the combination with a throttle valve controlling the outflow of fuel mixture from the mixing chamber, of an auxiliary fuel supply means inside the mixing chamber, normally closed means for supplying fuel to a point in the carburetor posterior to the throttle valve, and a mechanism for adjusting the outlet of said auxiliary fuel supply means, said mechanism including a rotatably mounted part and upon the rotation of said part in one direction causing diminution in the flow of fuel and upon reversal of rotation causing increase in said flow and also opening said second mentioned means to allow fuel to flow therethrough.

15. 5. In a carburetor of the class described a fuel valve, means for operating the same manually, raw fuel passages normally out of communication with one another, and means by movement serving to open the communication between said passages, said means positively operated by the means for operating said fuel valve.

20. In testimony whereof I have hereunto subscribed my name in the presence of two subscribing witnesses.

CHARLES L. RAYFIELD.
